UNITED STATES PATENT OFFICE.

HENRY A. THEXTON, OF MINNEAPOLIS, MINNESOTA, ASSIGNOR OF ONE-HALF TO E. H. DAY, OF MINNEAPOLIS, MINNESOTA.

RADIATOR FOOT-REST.

1,310,552.

Specification of Letters Patent. Patented July 22, 1919.

Application filed June 16, 1916. Serial No. 103,922.

To all whom it may concern:

Be it known that I, HENRY A. THEXTON, citizen of the United States, resident of Minneapolis, county of Hennepin, State of Minnesota, have invented certain new and useful Improvements in Radiator Foot-Rests, of which the following is a specification.

The object of my invention is to provide a foot rest having means for mounting it on a radiator with provision for adjusting it axially to adapt it for radiator sections of different sizes and shape and for different locations of the radiator.

The invention consists generally in various constructions and combinations, all as hereinafter described and particularly pointed out in the claims.

In the accompanying drawings forming part of this specification,

Figure 1 is a side elevation of a radiator with my invention applied thereto,

Fig. 2 is an end elevation of the same,

Fig. 3 is a plan view, partially in section, showing the manner of mounting the device on the radiator and the provision for adjusting the foot rail on its supporting brackets,

Fig. 4 is a detail sectional view of one of the brackets on which the foot rail is mounted,

Fig. 5 is a transverse sectional view of the foot rail.

In the drawing, 2 represents a radiator of ordinary construction. 3 represents a bolt or rod, square in cross section, having a head 4 at one end. A bar 5, preferably in the form of a channel, is loosely mounted on the end of the bolt to contact with the inner face of adjoining radiator sections and be held against the same by the head 4. The bolt 3 has a threaded end 6 and a plate 7 is mounted thereon to move back and forth toward and from the bar 5. A shank 8 has a central orifice 9 to receive the outer end of the bolt and is interiorly threaded at 10 to engage the threads of the bolt. The outer end of the shank has a ball 11 formed thereon having a slot 12 to receive a screw driver for the purpose of obtaining the desired adjustment to clamp the adjacent sections of the radiator between the plate 7 and the bar 5. When these sections are clamped, as indicated in Fig. 3, the inner end of the bracket 8 will be

in contact with the plate 7 and present a neat, ornamental appearance on the outer face of the radiator.

I prefer to provide two of these bolts and their attachments, located a suitable distance apart on the radiator and corresponding substantially in shape and size, each shank having a substantially spherical ball at its outer end that is adapted to slip into the tube 13 with the shank slidable in a slot 14 in the inner wall of the tube. At each end of the tube is a head 15 provided with a neck 16 to fit snugly into the open end of the tube and be secured therein by a set screw 17. These heads may be suitably finished, as well as the tube and the shank, to present a neat, ornamental appearance on the radiator.

The balls 11 fit snugly within the tube and cannot be separated therefrom until one of the heads 15 has been removed. Whenever desired, the tube may be moved lengthwise on the balls to change the position of the rest with respect to the radiator and whenever desired, the shanks may be loosened and their position changed to raise or lower them on the sections and vary the height of the rest or move them with the rest to another position on the radiator.

By providing the bolt 3 preferably square in cross section, I am able to tilt the bar 5 up to a vertical position and insert it between the adjoining sections of the radiator and then turn it down to its horizontal clamping position. The plates 7 may then be seated against the outer face of the sections and clamped by means of the shanks 8.

The bar 5 is loosely mounted on the bolt 3 and may adjust itself to the uneven surface of the radiator sections and may also be readily detached from the bolt for convenience in packing.

A device of this kind is extremely rigid, as the double bearings of the shank on the sections serve to hold them very firmly, and the manner of supporting the tubular rest on the shanks insures a very firm, substantial support for the feet and at the same time makes provision for convenient endwise adjustment of the tube whenever desired.

The device may be applied to any style and size of radiator and for a long rest a greater number of shanks may be used.

In various ways the details of construc-

tion herein shown and described may be modified and still be within the scope of my invention.

I claim as my invention:

- 5 1. A radiator foot rest comprising bolts having shanks and heads at the inner ends thereof, bars loosely mounted on said inner ends to bear on the inner faces of the radiator sections and free to slide and tilt thereon to fit the inequalities of the radiator sections, said bolts projecting outwardly between the radiator sections and having threaded outer ends, plates loosely mounted on said bolts to bear on the outer faces of said sections and shanks interiorly threaded to receive the threaded ends of said bolts for clamping said plates and bars against the inner and outer faces of said sections, and a foot rail carried by said shanks.
- 10 15 20 25 2. A radiator foot rest comprising bolts having shanks, polygonal in cross section and heads at the inner ends of said shanks, bars loosely mounted on said shanks for bearing on the inner faces of the radiator sections and accommodating themselves to the inequalities thereof, the outer ends of said bolts being threaded and projecting between the radiator sections, plates loosely

mounted on said bolts to bear on the outer faces of said sections, and shanks interiorly threaded to receive the threaded ends of said bolts for clamping said plates and bars against the inner and outer faces of said sections, and a foot rail carried by said shanks.

3. A radiator foot rest comprising bolts having heads at their inner ends, channel bars loosely mounted on said bolts and seated against said heads and having a limited rocking movement thereon, the edges of said channel bars being seated against the inner faces of the radiator sections and said bars tilting on said bolts to adjust themselves to the uneven surfaces of said sections, said bolts projecting outwardly between the radiator sections, plates loosely mounted on the outer ends of said bolts to bear on the outer faces of said sections, and shanks interiorly threaded to receive the threaded ends of said bolts for clamping said plates and bars against the inner and outer faces of said sections, and a foot rail carried by said shanks.

In witness whereof, I have hereunto set my hand this 9th day of June, 1916.

HENRY A. THEXTON.
